UNITED STATES PATENT OFFICE

AXEL OLOF ENGBERG AND LARS ELL, OF STOCKHOLM, SWEDEN, ASSIGNEES, BY MESNE ASSIGNMENTS, TO ELECTROLUX CORPORATION, A CORPORATION OF DELAWARE

SUCTION CLEANER NOZZLE

Application filed October 15, 1926, Serial No. 312,653, and in Germany August 7, 1926.

Our invention relates to vacuum cleaner nozzles and particularly to nozzles comprising bristles which are relatively soft and which are adapted for picking up fluff and 5 threads.

The invention will be understood from the following description taken in connection with the accompanying drawings showing several embodiments thereof, which drawings 10 constitute a part of this specification and, of which:

Fig. 1 is a view principally in cross-section of a nozzle in accordance with the invention; and

15 Fig. 2 is a side view of the nozzle shown in Fig. 1 in accordance with the invention.

Our improved nozzle includes a body member consisting of an annular plate or ring *n* which is preferably made of any mouldable 20 material such as bakelite or the like. Plate *n* is secured to a connecting member *e* by means of screw bolts *o* and nuts *p*. The nuts *p* are preferably moulded fast into plate *n*. Bristles *q* are secured in plate *n* and extend 25 downwardly as shown. Within the bristles, so as to be surrounded thereby, is a resilient hollow member *r*. Member *r* has a rounded middle portion and a lower edge which is inturned and curved upwardly, as shown, toward the body member *n*. Member *r* passes 30 within the central opening in plate *n* and has an upper flange *t* which covers the upper side of plate *n*. Integral with flange *t* is a downturned edge *u* which covers the outer 35 edge of plate *n*. Since member *r* is made of resilient material, this edge *u* serves as a protection for furniture and other articles being cleaned. Flange *t* is held between connecting 40 member *e* and plate *n* by means of bolts *o* and nuts *p*. The joint is simple in construction and yet provides an air-tight joint. Since the rubber or other resilient material of which member *r* is made may deteriorate 45 after a period of time, the construction is such that this member may be replaced from time to time. The replacement is effected by unscrewing screws *o* and separating the parts. The nuts *p* remain in plate *n*.

50 The bristles *q* extend downwardly around and beyond the member *r*. These bristles are

relatively soft and are designed to bend in operation of the nozzle. The rounded surface of hollow member *r* prevents undue bending of the bristles and thereby protects the bristles from injury. Due to the construction and arrangement of the parts, the bristles lie along the curved surface of member *r* and follow the line of flow of the suction air. Consequently, small threads, dirt and the like cannot remain therein. It will be appreciated 55 that the member *r* is bendable and that bending of the same varies the suction opening. The connecting member *e* is connected to the suction tube of a vacuum cleaner and air is drawn through the bristles, through the member *r* and through the connecting member *e* to the suction-producing means. 60

While we have illustrated and described one form of the invention, it will be understood that the invention is not limited to the form described but is to be gauged by the terms of the appended claims taken in conjunction with the state of the prior art. 70

What we claim is:

1. A nozzle for vacuum cleaners comprising an annular member, a hollow member made of resilient material having a rounded portion extending downwardly from said annular member, the upper portion of said hollow member extending through said annular member and over the top side and outside edge thereof, and bristles secured in said annular member extending downwardly around and beyond said rounded portion. 75

2. A nozzle for vacuum cleaners comprising an annular member, a hollow member made of resilient material having a rounded portion extending downwardly from said annular member, the upper portion of said hollow member extending through said annular member and over the top side and outside edge thereof, and bristles secured in said annular member extending downwardly around and beyond said rounded portion having an inturned edge. 80

3. A nozzle for vacuum cleaners comprising an annular member, a hollow member made of resilient material having a rounded portion extending downwardly from said 85 100

annular member, the upper portion of said hollow member extending through said annular member and over the top side and outside edge thereof, bristles secured to said annular member extending downwardly around and beyond said rounded portion, and a connecting member, said hollow member being secured between said connecting member and said annular member.

4. A nozzle for vacuum cleaners comprising an annular member, a hollow member made of resilient material having a rounded portion extending downwardly from said annular member, the upper portion of said hollow member extending through said annular member and over the top side and outside edge thereof, bristles secured to said annular member extending downwardly around and beyond said rounded portion, a connecting member and means for securing said hollow member between said connecting member and said annular member comprising screw bolts passing through the connecting member, the annular member and the hollow member, and nuts for said bolts embedded in the annular member.

In testimony whereof we have hereunto affixed our signatures.

AXEL OLOF ENGBERG.

LARS ELL.
